UNITED STATES PATENT OFFICE.

WALTER A. WELLS, OF CHICAGO, ILLINOIS.

DESIGN FOR A GAME-BOARD.

SPECIFICATION forming part of **Design No. 23,101**, dated **March 6, 1894**.

Application filed February 1, 1894. Serial No. 498,797. Term of patent 7 years.

To all whom it may concern:

Be it known that I, WALTER A. WELLS, a citizen of the United States, and a resident of Chicago, county of Cook, and State of Illinois, have invented and produced a new and original Design for Game-Boards, of which the following is a full, clear, and exact description, reference being had to the accompanying drawing, making part of this specification.

The leading features of my design consist in the squares of different colors, around a circle in the center of the game board; in the four stars with the open centers, located outside of and beyond the squares; also in the octagonal band forming the boundary of and surrounding the squares, and in the filigree work, composed of concentric circles, as shown in the drawing.

The accompanying drawing represents a plan or face view of my game board.

A indicates a circle, which forms the center of the game board.

B, B', B² and B³, indicate series of squares, of different colors, surrounding the circle A, 25 each of the series differing from the others in shading or color, so as to be readily distinguishable.

C, C, are stars, with open circular centers; they are four in number and are located one 30 at each corner of the design.

D represents a band or boundary line, being octagonal in contour and surrounding the squares B, B', B² and B³, as shown, and also lying between and separating the squares 35 from the stars C.

What I claim is—

The design for a game board, herein described and shown.

In testimony whereof I have hereunto set 40 my hand this 30th day of January, 1894.

WALTER A. WELLS.
